UNITED STATES PATENT OFFICE.

CHARLES OSBORNE, OF NORTH ATTLEBOROUGH, MASS., ASSIGNOR TO
THE WHITING MANUFACTURING COMPANY, OF NEW YORK, N. Y.

DESIGN FOR BORDER FOR SILVER-WARE.

Specification forming part of Design No. 7,623, dated August 4, 1874; application filed June 29, 1874.
[Term of Patent 7 years.]

CASE B.

To all whom it may concern:

Be it known that I, CHARLES OSBORNE, of North Attleborough, Bristol county, in the State of Massachusetts, have invented a new and original Design for Border for Silver-Ware and analogous goods, of which the accompanying drawing or photograph, with this specification, is a full and complete description.

The drawing is a face view of a short length of the border shown on a dark ground.

Along the center is a series of rectangles, *a*, placed diamondwise, and carrying on each an ornament, *b*, in radiating lines. Each edge is formed by a fascia or raised band, *j*. A grained surface, *h*, separates this from a milled or corded bead, *i*. The field *m* between these inner beads *i* and the diamonds *a* is wattled with delicate fillets, as follows: Curves *c* sweep around to connect the salient angles; corresponding curves *d* cross these, and connect the re-entering angles, while curved fillets *e* and longer straight fillets *g*, each with its end swelled or knobbed, extend from near

the latter angles, and are distributed in the spaces inclosed by the curves *c* and *d*.

The pattern or design may be varied in size, and in the precise arrangement of the details, so long as they form essentially the same design and produce the same ornamental and distinctive effect.

What I claim as my design for border is—

1. The diamond-shaped figure *a* and radial ornaments *b* on the wattled field *m*, as shown and described.
2. The fillets *c d e g* on the field *m*, with the series of central ornaments *a b*, as shown and described.
3. The edge-beads *h i j*, central ornaments *a b*, and wattled field *m*, as shown and described.

In testimony whereof I have hereunto set my hand this 25th day of June, 1874, in the presence of two subscribing witnesses.

Witnesses: CHARLES OSBORNE.

THOS. G. SANDLAND,
HENRY E. CAPRON.
